UNITED STATES PATENT OFFICE.

FREDERICK E. MEINEL, OF WILMETTE, ILLINOIS, ASSIGNOR TO ILLINOIS SHOW CASE WORKS, OF CHICAGO, ILLINOIS, A CORPORATION OF ILLINOIS.

SUPPORT FOR DISPLAYING COLLARS.

1,250,482.

Specification of Letters Patent. Patented Dec. 18, 1917.

Application filed April 27, 1917. Serial No. 164,857.

To all whom it may concern:

Be it known that I, FREDERICK E. MEINEL, a citizen of the United States, residing at Wilmette, county of Cook, State of Illinois, 5 have invented a certain new and useful Improvement in Supports for Displaying Collars, and declare the following to be a full, clear, and exact description of the same, such as will enable others skilled in the art to 10 which it pertains to make and use the same, reference being had to the accompanying drawings, which form a part of this specification.

My invention has for its object to produce 15 a simple and novel device for supporting either a soft or a starched turned-over collar for display in a showcase or otherwise, in such a manner that the lines of the collar will be displayed advantageously, and without having the appearance of the collar marred by exposed supporting or shaping devices.

A further object of the present invention 20 is to produce a simple collar-supporting device which will permit a collar to be readily adjusted in any one of a variety of positions varying from the approximately circular shape that it has when in place about the neck of a wearer to a completely flattened condition.

The various features of novelty whereby 25 my invention is characterized will hereinafter be pointed out with particularity in the claims; but, for a full understanding of my invention and of its objects and advantages, 30 reference may be had to the following detailed description taken in connection with the accompanying drawing, wherein:

Figure 1 is a front view of a collar arranged on one of my improved supporters, 35 the front corners of the collar being broken away;

Fig. 2 is an elevation of the supporter removed from the collar; and

Fig. 3 is an edge view of the clip shown 40 in Fig. 1, indicated as attached to the wall of a showcase illustrated in section.

The supporter consists of a long strip of 45 soft sheet metal which may readily be bent and which will retain any shape into which it is bent. For the sake of economy of material it is preferably made of a V-shaped central member having wings, 2 and 3, projecting laterally from the outer ends of its arms. 50 The wings 2 and 3 are preferably curved so

that a line connecting the free ends thereof passes through the central member in the vicinity of its apex. The depth or height of the central member is preferably no greater than the height of the rear portion of a 60 comparatively low collar, and the overall length or width of the device measured from the top of one wing to the top of the other is made less than the circumferential length 65 of the smallest collar that is to be supported.

The use of the device is illustrated in Fig. 1 in which 4 represents a turned-over collar between the inner and outer member of which the supporting device is inserted; the V-shaped central member 1 being placed 70 centrally at the back of the collar and the two wings being carried forwardly between the folds. The collar illustrated is a soft collar which has been flattened after the insertion of the supporting device, the softness of the supporter permitting the wings to be folded upon each other between their ends, and the supporter having sufficient stiffness thereafter to hold the collar in the shape in which it has been placed. In the 75 case of a starched collar, the supporter would of course be bent into a C-shape, which would also be the shape that it would take if it were desired to support the soft collar in an open condition.

In order to mount the collar in a showcase or elsewhere, I have provided a spring clip, 5, which may be attached to the wall, 6, of the showcase, or other supporting wall; the outer fold and the apex of the supporter being inserted behind the clip, so that no part of the collar is concealed either by the clip or by the supporting device. At the same time, the collar may readily be detached for 80 inspection.

While I have illustrated and described 85 with particularity only a single preferred form of my invention, I do not desire to be limited to the exact structural details thus illustrated and described; but intend to 90 cover all forms and arrangements which come within the terms employed in the definitions of my invention constituting the appended claims.

I claim:

1. A device of the character described made of soft non-resilient sheet metal having a length greater than one-half the length of a collar to be supported and being comparatively narrow, whereby the device may 100 105 110

be inserted in a soft collar and the ends be bent inwardly toward each other in flattening the soft collar so as to support the collar in a flattened condition.

- 5 2. A device of the character described made of soft non-resilient sheet metal and comprising a V-shaped central member and downwardly curved wings extending later-

ally from the top of the central member, the device having a length considerably greater than one-half the length of a collar to be supported.

In testimony whereof, I sign this specification.

FREDERICK E. MEINEL
